CHUCK

Ray W. Johnson, Chicago, Ill.

Application November 19, 1936, Serial No. 111,660

10 Claims. (Cl. 242—68)

This invention relates to chucks, and is particularly concerned with chucks of the type adapted to be employed in combination with a shaft for holding rolls of paper or other materials which are to be mounted on a shaft for wrapping or unwrapping.

The devices of the prior art are subject to the disadvantage that the engaging jaws have an axial movement with respect to the shaft on which the roll is mounted, and thus it is frequently found that after the roll has been secured in place the paper is out of alignment with the other mechanism of the press or other machine in which the paper is used.

One of the objects of the invention is the provision of an improved chuck for paper rolls or the like in which the engaging jaws do not have an axial movement with respect to the roll which they secure and engage, thereby assuring the securement of the roll in aligned position, once it is moved into that position.

The devices of the prior art are also subject to the disadvantage that the jaws are actuated by rotatable threaded members, and the threaded parts of those chucks have to be so arranged with a left hand and a right hand thread that they will be tightened by the rotation of the shaft. However, such devices are frequently loosened when the shaft is temporarily rotated in the other direction, or the mechanics may become confused in the assembly of the devices so that the threads may be wrongly arranged.

Another object of the invention is the provision of an improved chuck for paper rolls or the like which does not require any right hand or left hand threaded members, so that the chuck is not loosened by rotation in the opposite direction and there is no possibility of assembling the chuck with the shaft in the wrong way.

Another object of the invention is the provision of an improved chuck of the class described, the jaws of which are adapted to be brought into tight engagement with the interior of a paper roll by the peripheral motion of certain parts rather than the axial motion thereof, thereby assuring the alignment of the roll after the chuck is secured to the roll.

Another object of the invention is the provision of an improved chuck of the class described, which has means for securing the jaws in any of a plurality of predetermined positions, which securing means is adapted to effect the securement of the jaws upon relatively small steps of movement so that there is little or practically no backlash or backward movement of the actu-

ating mechanism of the chuck in order to effect securement.

Another object of the invention is the provision of an improved chuck of the class described which is adapted to be quickly and easily released by means of a special tool.

Another object is the provision of an improved chuck of the class described which is adaptable for use on either end of the paper roll or shaft and which is sturdy, economical, and capable of manufacture with a minimum amount of machine operations.

Other objects and advantages of the invention will be apparent from the following description and the accompanying drawings, in which similar characters of reference indicate similar parts throughout the several views.

Referring to the three sheets of drawings accompanying the specification,

Fig. 1 is a fragmentary diagrammatic view of a pair of chucks constructed according to the invention, mounted on a roll supporting shaft, showing the usual mode of use of such chucks;

Fig. 2 is a fragmentary vertical sectional view, taken through the mechanism of Fig. 1, on the plane 2—2 of Fig. 6, passing through the axis of the shaft;

Fig. 3 is a sectional view, taken on the plane of the line 3—3 of Fig. 1, looking in the direction of the arrows, and showing the jaw securing mechanism;

Fig. 4 is a vertical sectional view, taken on the plane of the line 4—4 of Fig. 1, looking in the direction of the arrows, showing the means for moving the jaws into engagement with the interior of the roll;

Fig. 5 is an elevational view of a combination wrench and chuck-releasing tool;

Fig. 6 is a sectional view, taken on the plane of the line 6—6 of Fig. 1, looking in the direction of the arrows, showing the means for securing the chuck to the shaft;

Fig. 7 is a view in perspective of the mechanism with the jaw retaining housing and the jaws removed;

Fig. 8 is a view in perspective of the jaw retaining housing, partially broken away to show the groove for the jaw flanges; and

Fig. 9 is a view in perspective of one of the jaws of the chuck, shown in such a position relative to Fig. 8 as to permit its ready insertion.

Referring to Figs. 1 and 2, 10 indicates in its entirety one chuck, and 11 the other chuck, mounted on a shaft 12 for the purpose of securing a roll of paper 13 to the shaft. The shaft 12 is

5 rotatably mounted in the bearings 14, 15, and is adapted to be removed from the bearings for the purpose of passing the shaft through the cylindrical core 16 upon which the paper of the 10 roll 13 is usually wound. It will be observed that the chucks 10 and 11 are oppositely disposed on the shaft 12, but otherwise these chucks are identical in construction and interchangeable so that there is no possibility of wrong assembly of the 15 chucks with the shaft.

10 Referring to Figs. 7 and 8, I shall now describe one of the chucks in detail. The chuck preferably includes a plurality of jaws 17 of identical construction, and any number of jaws may be 15 used, but I prefer to use three separate jaws in the preferred embodiment, and have numbered them 17, 18, and 19 in Fig. 4.

15 Each of these jaws comprises an elongated cast metal member which is curved like part of a cylinder, and which is provided at its end with the retaining flanges 20. The outer surface 21 of each jaw may be substantially cylindrical, and it may, if desired, be provided with a plurality of grooves 22, giving the outer face 21 of the jaw 25 a serrated surface, but I have found such serrations are not necessary.

20 The cylindrical surface 21 is substantially complementary to the cylindrical bore 23 on the inside of the cardboard core 16 of the paper roll 30 13, but each jaw covers less than one-third of the periphery of the interior of the core 16 so as to permit enough clearance so that the jaws may contract and expand within a core 16.

25 The inner curved surface 24 of each jaw is not cylindrical, but diverges from the cylindrical form by curving farther inward at the point 25 than its location at the point 26; that is, the jaw is made thicker at the top of Fig. 9 than it is at the bottom of Fig. 9, and thus the inner surface 40 24 is a camming surface, the upper portion of which in Fig. 9 is disposed at a lesser radius from the center of the shaft than the lower portion.

30 Each of the jaws 17-19 is also provided with an alignment flange 27, comprising a radially extending flange located on its outer surface 21 at a point slightly spaced from the jaw supporting housing 28, and adapted to engage the end of the paper roll 13. This flange determines the 45 position of the jaws in the core 16 of the paper roll.

35 The retaining flange 20 may comprise an integral radially and outwardly projecting flange, having a straight outer edge 28, and provided at each end with a thickened column 30. The thickened column portions 30 are of such thickness that they fit within the grooves 31, which are formed in the jaw supporting housing.

40 The jaw supporting housing 28 comprises a part of the chuck head 32. It is a cast metal member of annular shape, having two flat annular end walls 33, 34 joined by a frusto-conical side wall 35. The end wall 33 has a bore 36 which is of sufficient size to pass the camming member 37 45 (Fig. 7) to facilitate assembly with that part. The end wall 34 has a larger bore 38, the size of these bores differing by an amount which is equal to the largest thickness at the point 25 of a jaw 24. Between the annular end walls 33 and 34 50 there is located the groove 31, this groove being divided into three separate pockets 31 by the equally spaced partitions 39.

55 The retaining flanges 20, with their enlarged portions 30, are adapted to fit in the grooves or sockets 31, radial movement being permitted, the

enlarged portions 30 slidably engaging the walls of the sockets 31.

5 A portion of the frusto-conical outer wall 35 is cut away at 40, so that when this part of the housing is assembled with the other part 41, which comprises a ratchet housing, there is an aperture 42 for the passage of a force-multiplying lever 43.

10 The chuck-retaining housing is provided with a laterally projecting cylindrical wall 44, serving as part of a housing for the ratchet mechanism, and it is provided with screw supporting lugs 45, located to be aligned with similar screw supporting lugs on the ratchet housing 41 (Fig. 7). Screws passing through the ratchet housing 41 15 and threaded into bores in the jaw retaining housing 28 secure these two parts together to form the chuck head.

15 Referring to Fig. 7, the chuck is preferably provided with means for positively securing the chuck head 32 to the shaft 12, comprising the relatively heavy cylindrical extension 46, forming a collar which is separated from the housing 41 half-way as by a groove 47.

20 Collar 46 is also split radially at the slot 48 25 (Fig. 7), and the two legs 49, 50 are joined by a threaded member 51, located in the bore 52 and threaded into an aligned bore in the leg 50. Threaded member 51 has a non-circular socket 53 for reception of the non-circular (hexagonal) 30 bent end 54 of the wrench and releasing tool 55 (Fig. 5). By means of the collar 46 it is possible to clamp each chuck in proper position on the shaft 12 simply by driving the threaded member 51 home into a threaded bore in the 35 leg 50.

25 The housing member 41 is provided with a radially extending supporting flange 56 and with an outer cylindrical flange 57, the latter being also cut away at 58 at a point which registers 40 with the cut-away portion 40 of the housing 28. This housing member is provided with a cylindrical bore 59 for receiving the shaft 12, and it is secured to the housing member 28 by a plurality of screw bolts 60 (Fig. 3). The flange 56 45 is provided with apertures for receiving the spring supporting pins 61, 62. It is also provided with an aperture for receiving the pivot pin 63 for a plurality of pawls 64-67. The pins 61-63 may have a sliding fit in the bores in 50 the flange 56, and also a sliding fit in similarly located bores in the flange 33 of the housing member 28.

55 Flanges 56 (Fig. 7) and 33 and 34 (Fig. 8) are each provided with the through bore 68 to permit passage of the cylindrical end 69 (Fig. 5) of the chuck releasing tool from either side of the chuck head, although the tool can only be inserted from the left of Fig. 1 when a roll is on the chuck. The action of this tool will be described in detail later.

60 Each of the pawl members 64-67 is of the same shape, but the pawls are successively longer, as shown in Fig. 3. Each pawl comprises a steel member which is provided with an inwardly projecting tooth 69 at one end, a bearing aperture 70 between its ends, and with a grooved tail 71 at the opposite end. The groove in the tail 71 is located on the inner side in Fig. 3, as shown by the dotted lines at 72, and is 70 adapted to receive one end of the longer arm 73 of a spring 74.

65 The pawls are pivotally mounted on the pin 63 for engagement with the teeth 75 of a ratchet sector 76. Only one pawl actually engages a 75

tooth at one time, but the pawls being of successive length, all within the spacing between two teeth, it will be observed that the sector 16 may be engaged by any one of the four pawls, 5 depending on its position, and thus the increments of movement and points of securement of the sector 16 are varied by extremely small spaces, differing only by the difference in length of the pawls 64—67.

10 Each of the springs 74 comprises a relatively long arm 73, a coiled portion 77 coiled about the pin 61, and a short arm 78 engaged outside of the pin 62.

The springs are placed under such tension that 15 they pivot the pawls in a counter-clockwise direction in Fig. 3, to urge them into engagement with the ratchet sector 76. They may be moved out of engagement with the tooth 15 of the ratchet sector 76 by the camming action of the 20 frusto-conical end 79 of the tool 55 when thrust into the bore 68, from either end of the head.

The tool is to be inserted in Fig. 3, the cylindrical portion 69 engaging the tails 71 of all 25 of the pawls 64—67, and holding them out of engagement. This shows the action of the tool in releasing the pawls from the ratchet sector so that the clutch may be released when the tool is removed, the pawls automatically engaging the teeth.

30 Referring to Fig. 7, the chuck is provided with a camming member 37, comprising a substantially cylindrical or tubular cast metal member which is provided with a multiplicity of integral camming formations 80. The cams 80 are merely ribs 35 or thickened portions on the cylindrical wall of the tube 37, and it will be observed that at the cams 80 this wall increases in thickness in a clockwise direction in Fig. 7.

The cams 80 are preferably located at equally 40 spaced points along the length of the tubular member 37 and arranged at equally spaced points about its periphery. In the present case, where three jaws are used, three series of cams 80 are equally spaced about the periphery of the camming member 37 and located to engage the jaws 17—19. The endmost cam 80 is provided with a tapered surface 81 to facilitate the insertion of this camming member through the bore in the housing member 32.

50 The camming member 37 is provided with a cylindrical bearing flange 82 at its left end (Fig. 7), the bearing flange 82 fitting within the bore 36 (Fig. 8) for rotatable support of the camming member in the housing. The camming member 55 is also provided with an enlargement or head 83, which has a radially extending body 84 provided with an aperture 85 that is rectangular in cross section so as to receive the rectangular bar 43.

The rectangular bar 43 may be of considerable 60 length, as, for example, 12 to 18 inches, so as to permit considerable force to be applied to the rotation of the camming member 37. Lug 84 is provided with a pair of outwardly projecting lugs 87 and 88, which are of the same thickness as 65 the bar 43, and which are adapted to project between the edges 58 and 40 of the cut-out portions of the housing. Camming member 37 is provided with a cylindrical bore 89 for receiving the shaft 12, and this bore is split by a slot 90, 70 which extends throughout the effective length of the tubular member 37. The bore 89 communicates with a counterbore 86 at the end flange 91 of the camming member, and counterbore 86 is adapted to receive an inwardly projecting cylindrical bearing flange 92, carried by the housing 75

member 41, providing another bearing for the head 83 of the camming member 37.

Head 83 of the camming member 37 is provided with a peripherally extending groove 93 (Fig. 2), which extends over approximately one-third of 5 the periphery of the head, and which is adapted to receive the ratchet tooth sector 76 of complementary shape.

The ratchet tooth sector 76 comprises a curved member, having a radially, inwardly extending lug 94, which extends into bore 95 in the tubular member 37. Lug 94 is adapted to bear the major portion of the load on the ratchet tooth sector 76, and positively prevents rotation of this sector 10 with respect to the camming member 37, but the 15 ratchet member is secured in place by a plurality of through-screw bolts 96, which are threaded into the flange 91.

The method of assembly of the parts is as follows: The tool 55 may have its end 69 inserted in 20 the bore 68 of the housing member 41, and the pawl members 64—67 may then be assembled on this housing member, with the springs and pins. The three jaw members 17—19 may be inserted 25 with their flanges 29 in the sockets 31 of the housing member or collar 28. The camming member 37 may then be inserted between the jaws 17—19 and rotated until the lugs 87, 88 are located in the groove 42. The housing members 41 and 32 may 30 then be placed together, with the bores that receive the screw bolts 69 in registry, and they may be secured together by the screw bolts.

Thereafter the tool 55 may be removed to permit the pawls 64—67 to come into engagement 35 with the ratchet sector.

The use and operation of the chucks is described as follows: The shaft 12 is inserted through the core 16 of a roll of paper, with a chuck 10, 11 at each end of the roll. The jaws 17—19 of each chuck are inserted into the core 40 16 until the flange 27 engages the end of the core, and the collar 46 of each chuck is secured in place by the threaded member 51, which draws the legs 49, 50 of the collar together and clamps the collar on the shaft in the position of Fig. 1. 45 The roll 13 is then secured on the shaft by means of the chucks, as follows:

A bar 43 is inserted in its socket 85, and the camming member 37 is rotated by moving the bar downward in Fig. 7; that is, in such direction 50 as to rotate the cams 80 counter-clockwise in Fig. 7. The thickened portions of the cams 80 come into engagement with the thickened portions 25 of the jaws 17—19 simultaneously, and effectively spread the jaws 17—19 into engagement with the core 16. As the camming member 37 is rotated, the pawls 64—67 are constantly urged toward the teeth 15, and one of the pawls 55 is always in position to engage one of the teeth. The camming member 37 will be held by the 60 pawls 64 in substantially the position to which it is moved, with only a minimum amount of back movement or backlash, amounting to the difference in length between successive pawls 64—67. The roll having once been aligned with the press or other mechanism with which it is being used by location of the chuck 10, it cannot 65 get out of alignment by any action of the chucks because the chucks merely spread their jaws radially and do not slide longitudinally of the 70 roll.

Both chucks are identical in construction, and there is no possibility of wrong assembly of the chucks with the shaft, and since there are no threaded members which can be loosened by ro- 75

tation of the shaft, the securement of the roll by the chucks is assured at all times.

The chucks do not depend solely on the collars 46 for their securement to the shaft because this 5 securement is augmented by the spreading action of the cams 89 and jaws 17-19, which acts on the split sleeve 37 to compress that sleeve into closer engagement with the shaft 12. The chuck thus has the complete length and full internal 10 area of the sleeve 37, as well as the collar 46, for frictional engagement with the shaft 12 to secure each chuck to the shaft.

The securement of the chuck to the paper roll effectively secures the chuck more tightly to the 15 shaft. After the roll has been secured by means of a chuck at each end, the bar 43 is, of course, removed. The chuck may be released at any time by merely forcing the conical end 79 of the tool 55 into the bore 68. The conical end 79 cams the 20 pawls 64-67 out of engagement with the sector 76 and releases the chuck. This may be made easier by inserting the bar 43 and relieving the pressure on the teeth at the same time the tool 25 55 is inserted. The insertion of the tool 55, however, permits the camming sleeve 37 to be rotated to released position at once so that the chucks immediately release the roll.

It will thus be observed that I have invented 30 a new chuck for use in securing paper rolls or the like to a shaft.

The present chuck is quick and positive in its action and, as stated before, it is not loosened by any rotation of the shaft. Its parts comprise 35 castings which require a minimum amount of machining, and it may, therefore, be constructed at a very low cost. The chuck facilitates the alignment and securement of the roll in proper position, and the action of securing the paper roll by the chuck does not change the alignment of 40 the roll.

While I have illustrated a preferred embodiment of my invention, many modifications may be made without departing from the spirit of the invention, and I do not wish to be limited to the 45 precise details of construction set forth, but desire to avail myself of all changes within the scope of the appended claims.

Having thus described my invention, what I 50 claim as new and desire to secure by Letters Patent of the United States, is:

1. In a chuck for securing a hollow member to a shaft, the combination of a supporting head with a rotatable camming sleeve adapted to be mounted on the shaft, a plurality of jaws extending longitudinally of the shaft and located outside of said sleeve, said jaws and sleeve comprising camming means operating between said jaws and said sleeve by the rotation of said sleeve for spreading said jaws into engagement with a hollow member to be secured to the shaft, pawl and ratchet means carried by said head and sleeve for securing said sleeve in any of a plurality of predetermined rotative positions, and means for slidably engaging said pawl means to release said 65 pawls from the ratchet and effect a release of the chuck, said latter means comprising a tool having a camming end adapted to be inserted in a bore in said head.

2. In a chuck for securing paper rolls or the 70 like to a shaft, the combination of an annular head provided with a bore extending through the same, a sleeve rotatably mounted in said bore and having peripherally extending camming means on its outer surface, and a plurality of jaws having parts thereof expansively mounted

in said head, said jaws having camming formations on their inner surfaces whereby rotation of said sleeve spreads said jaws into engagement with a member to be fastened to a shaft, said head having inwardly open, curved sockets, and 5 said jaws having outwardly extending flanges for engagement in said sockets.

3. In a chuck for securing paper rolls or the like to a shaft, the combination of an annular head provided with a bore extending through the 10 same, a sleeve rotatably mounted in said bore and having peripherally extending camming means on its outer surface, and a plurality of jaws having parts thereof expansively mounted 15 in said head, said jaws having camming formations on their inner surfaces whereby rotation of said sleeve spreads said jaws into engagement with a member to be fastened to a shaft, said sleeve being provided with ratchet teeth adjacent said head, and pawl means in said head for 20 securing said sleeve in any of a plurality of rotative positions.

4. In a chuck for securing paper rolls or the like to a shaft, the combination of an annular head provided with a bore extending through the 25 same, a sleeve rotatably mounted in said bore and having peripherally extending camming means on its outer surface, a plurality of jaws having parts thereof expansively mounted in said head, said jaws having camming formations on 30 their inner surfaces whereby rotation of said sleeve spreads said jaws into engagement with a member to be fastened to a shaft, said sleeve being provided with ratchet teeth adjacent said head, and pawl means in said head for securing 35 said sleeve in any of a plurality of rotative positions, said pawl means comprising a plurality of separately movable pawls having engaging teeth located within the space between two adjacent ratchet teeth.

5. In a chuck for securing paper rolls or the like to a shaft, the combination of an annular head provided with a bore extending through the 40 same, a sleeve rotatably mounted in said bore and having peripherally extending camming means on its outer surface, a plurality of jaws having parts thereof expansively mounted in said head, said jaws having camming formations on their inner surfaces whereby rotation of said sleeve spreads said jaws into engagement with a member to be fastened to a shaft, said sleeve being provided with ratchet teeth adjacent said head, and pawl means in said head for securing 45 said sleeve in any of a plurality of rotative positions, said head having a transverse bore located adjacent the pawls, and means slidably mounted in said bore for moving the pawls out of engagement with the adjacent ratchet teeth.

6. In a chuck for securing paper rolls or the like to a shaft, the combination of a supporting head adapted to be fixedly secured to a shaft, with a split sleeve adapted to be rotatably mounted on said shaft and rotatably mounted with respect to said head, said sleeve having a plurality of cams and being provided with parts adapted to clamp the shaft, a plurality of jaws having parts thereof movably mounted on said head for engaging the interior of a paper roll, and means for rotating said sleeve, whereby said jaws are expanded to engage the paper roll and the sleeve is contracted to engage the shaft, a ratchet carried by said sleeve, said sleeve having means for securing it selectively to the head in any of a plurality of adjusted positions, comprising a multiplicity of pawls located with their 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 engaging shoulders at increments of distance from each other which are less than the distance between the teeth of the ratchet.

7. In a chuck for securing paper rolls or the like to a shaft, the combination of a supporting head, said head having an inwardly open annular groove and having a sleeve rotatably mounted on said head, with a plurality of curved jaws extending longitudinally of said sleeve and exterior thereof, said curved jaws having flanges slidably mounted in said annular groove, said groove and flanges being of sufficient size to permit radial movement of said jaws, camming formations on said jaws and sleeve increasing in size in a peripheral direction, whereby when the sleeve is rotated the jaws will be expanded to engage the paper roll, and means for securing the sleeve in predetermined position with respect to the head, comprising a ratchet carried by said sleeve and a pawl carried by said head, said sleeve having a slot extending over the major portion of its length, whereby the sleeve may be urged into closer engagement with the shaft by the action of the camming means.

25 8. In a chuck for securing paper rolls or the like to a shaft, the combination of a supporting head, said head having an inwardly open annular groove and having a sleeve rotatably mounted on said head, with a plurality of curved jaws extending longitudinally of said sleeve and exterior thereof, said curved jaws having flanges slidably mounted in said annular groove, said groove and flanges being of sufficient size to permit radial movement of said jaws, camming formations on said jaws and sleeve increasing in size in a peripheral direction, whereby when the sleeve is rotated the jaws will be expanded to engage the paper roll, and means for securing the sleeve in predetermined position with respect to the head, comprising a ratchet carried by said sleeve and a pawl carried by said head, said sleeve having a slot extending over the major portion of its length, whereby the sleeve may be urged into closer engagement with the shaft by the action of the camming means, said head comprising a pair of circular parts, and said sleeve having an annular portion projecting radially therefrom secured between said parts for rotative movement.

50 9. In a chuck for securing paper rolls or the

like to a shaft, the combination of a supporting head, said head having an inwardly open annular groove and having a sleeve rotatably mounted on said head, with a plurality of curved jaws extending longitudinally of said sleeve and exterior thereof, said curved jaws having flanges slidably mounted in said annular groove, said groove and flanges being of sufficient size to permit radial movement of said jaws, camming formations on said jaws and sleeve increasing in size in a peripheral direction, whereby when the sleeve is rotated the jaws will be expanded to engage the paper roll, and means for securing the sleeve in predetermined position with respect to the head, comprising a ratchet carried by said sleeve and a pawl carried by said head, said sleeve having a slot extending over the major portion of its length, whereby the sleeve may be urged into closer engagement with the shaft by the action of the camming means, said sleeve having a radially extending lug provided with a handle socket and an elongated handle in said socket for rotating said sleeve.

10 10. In a chuck for securing paper rolls or the like to a shaft, the combination of a supporting head, said head having an inwardly open annular groove and having a sleeve rotatably mounted on said head, with a plurality of curved jaws extending longitudinally of said sleeve and exterior thereof, said curved jaws having flanges slidably mounted in said annular groove, said groove and flanges being of sufficient size to permit radial movement of said jaws, camming formations on said jaws and sleeve increasing in size in a peripheral direction, whereby when the sleeve is rotated the jaws will be expanded to engage the paper roll, and means for securing the sleeve in predetermined position with respect to the head, comprising a ratchet carried by said sleeve and a pawl carried by said head, said sleeve having a slot extending over the major portion of its length, whereby the sleeve may be urged into closer engagement with the shaft by the action of the camming means, said head having a shaft-engaging collar provided with split ends, and threaded means for drawing said split ends together to clamp said head to said shaft.

RAY W. JOHNSON.
